FIG. 1 is a front, bottom perspective view of a car charger and mount for hand-held electronic devices comprising a new, original and/ornamental design;
FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front, bottom perspective view of another embodiment of a car charger and mount for hand-held electronic devices comprising a new, original and/ornamental design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines shown in the drawings represent portions of the car charger and mount for hand-held electronic devices that form no part of the claimed design.

1 Claim, 10 Drawing Sheets
